ELECTRIC SWITCH

Kenneth C. Allison, Crystal Lake, Ill., assignor
to Grigsby-Allison Company, Inc., Arlington
Heights, Ill., a corporation of Delaware

Application June 4, 1952, Serial No. 291,749

8 Claims. (Cl. 200—15)

1

This invention relates to switches and particularly rotary electrical switches of the type wherein contact blades carried on a rotor cooperate respectively with spring jaw contacts on a stator surrounding the rotor whereby circuits may be selectively established between such stator contacts by rotation of the rotor.

The present invention is especially directed to a rotary switch of the character described which combines an index plate fixed to a bushing and a spring indexing member fixed to the protruding end of a shaft rotatably mounted in said bushing, and an insulating stator and an insulating rotor about said shaft between said indexing member and index plate. In former switches of this style it has been customary to lock the rotor and shaft by means of a rotor shaft receiving opening in the rotor having interfitting relation with a flattened portion on the shaft. As proposed in the switch of this invention, the angular position of the rotor relative to the shaft is controlled by the indexing member rather than through the cooperating surfaces of the shaft and the shaft receiving opening of the rotor with the result that the assembly is not only greatly facilitated but the fixed angular position of the rotor relative to the shaft is more positively maintained under conditions of hard use.

The switch contemplated by the present invention also provides for an index plate so joined to the stator as to provide especially rigid anchorage of the stator thereon.

With these and other objects in view, as may appear from the accompanying specification, the invention consists of various features of construction and combination of parts, which will be first described in connection with the accompanying drawings, showing a preferred embodiment of the invention, and the features forming the invention will be specifically pointed out in the claims.

In the drawings:

Fig. 1 is a side elevational view of a preferred form of switch embodying the present invention.

Fig. 2 is a top plan view thereof.

Fig. 3 is a detail view of the shaft and indexing member.

Fig. 4 is a section on line 4—4 of Fig. 1.

Fig. 5 is an enlarged section on line 5—5 of Fig. 4.

The switch embodying the features of this invention as illustrated in the drawing includes an insulating stator 10 and a metal base or index plate 11 to which the stator is secured in juxtaposed relation. As shown in Fig. 4, a bushing

2

12 has an end wall portion crimped as at 13 in overlapping relation to the edge 14 of an opening in the plate 11 while a collar 15 of hexagonal or similar shape having diametrically opposed flat sides formed integrally with the bushing 12 presents an annular face 16 against which the plate 11 is firmly seated about the edge 14 of the opening in the latter. Straight edge portions formed in diametrically opposite sections of the edge 14 of the opening in the plate 11 are offset from the plane of the plate, as at 17, in a direction to engage opposite faces 18 of the collar 15 of the bushing 12 whereby the plate 11 and bushing 12 are locked against relative rotation. The area of the plate 11 about the portion of the bushing 12 crimped to the edge 14 of the plate 11 and facing in the direction of the stator 10 is exposed through an opening 19 provided in the stator. Notches or recesses 20 formed in diametrically opposed edge portions of the stator opening 19 are designed to contain staking ears 21 formed integrally with the plate 11 to rigidly anchor the stator 10 on the plate 11.

As shown in Fig. 5, the ears 21 have opposed edge portions which have wedging fit with the walls of the notch 20 adjacent the end of the ears joined to the plate 11 as well as at the staked end of the ears. Thus stator 10 and plate 11 are drawn into a state of rigid assembly in a manner that positively assures a constantly fixed juncture of said parts against any relative angular movement.

Reference numeral 22 designates a cylindrical shaft rotatably supported in the bushing 12. A spring ring 23 seated in a circumferential slot provided in the body of the shaft 22 engages the edge 24 of the bushing 12 remote from the plate 11 so as to restrict movement of the shaft 22 axially of the shaft in the direction of the opposite edge 13 of the bushing. An insulating rotor 25 is formed with a central opening of such contour as to fit the circular contour of the shaft 22 protruding from the end portion 13 of the bushing. A spring metal strip 26 is locked to the shaft 22 by means of a tubular extension at the protruding end of the shaft 22 which is crimped as at 27 in overlapping relation to the edge of an opening of substantially square contour formed in the strip 26. The rotor is keyed to the shaft 22 by means of integral ears 28 and 29 on the strip 26 which diametrically straddle the end of the shaft facing the strip 26, and matching notches 30 formed in the edge of the shaft receiving opening in the rotor, as illustrated in Fig. 3. Thus the notches 30 in the shaft re-

ceiving opening in the rotor and the ears 28 and 29 on the strip 26 have interlocking engagement to maintain the rotor and shaft in fixed assembled relation for rotation in unison.

The end of the strip 26 extending radially away from the shaft 22, designated at 31, is bent to form a finger engageable with alternating depressions 32 and elevations 33 formed along a marginal portion of the plate 11 which is exposed beyond the periphery of the stator underlying said strip 26. Thus the rotor is stationed at selected positions of rotation according to the relative position of the spring strip 26 and the depressions and elevations on the exposed margin of the plate 11. Stops 34 and 35 at opposite ends of said marginal portion of the plate are operative to limit the movement of the strip 26 and the shaft 22 according to the arc of movement required to accomplish the desired switching action between spring jaw contacts 36 secured on the stator and the cooperating blade 37 of a contact member secured on the rotor. It will be observed that the contact member 37 is secured to the rotor by means of angular fingers which pierce the rotor and are staked to the face of the rotor in a position opposite the area of clearance between the stator and the radially opposite surface of the shaft 22.

What is claimed is:

1. An electric switch comprising an insulating stator having an opening through which an operating shaft projects, an insulating rotor having an opening through which said shaft projects, a metal base to which said stator is fixed, said base presenting a marginal portion beyond the peripheral limits of the stator, indexing means on said marginal portion of the base, and means through which the rotor is rotatively locked to the shaft including a spring member fixed to the shaft and having a radially extending finger cooperating with said indexing means, said spring member having integral members interlocked with notches formed in the rotor, and cooperating contacts on the rotor and stator.

2. An electric switch as defined in claim 1 wherein said integral members on the spring members are interlocked with notches formed in diametrically opposite edge portions of the opening in the rotor through which the operating shaft projects.

3. An electric switch as defined in claim 1

50

wherein integral members on the metal base are interlocked with notches formed in opposite edge portions of the opening in the stator through which the operating shaft projects.

4. An electric switch as defined in claim 1 wherein integral members on the metal base and notches formed in opposite edge portions of the opening in the stator through which the operating shaft projects have wedging fit.

5. An electric switch as defined in claim 1 wherein integral members on the metal base and notches formed in opposite edge portions of the opening in the stator through which the operating shaft projects have wedging fit circumferentially of the path of rotation of the shaft.

6. An electric switch comprising an insulating stator having an aperture therethrough, a metal base to which said stator is fixed in face to face relation and presenting a marginal portion beyond the peripheral limits of the stator, an opening in the plate in alignment with but of smaller size than the aperture in the stator, a bushing having an end portion to which the edge of the opening in the plate is fixed, a shaft rotatably mounted in said bushing and projecting beyond opposite ends of the bushing, an insulating rotor on the shaft portion projecting from the end of the bushing to which the base is fixed, said rotor being of such size as to overlap the edge of the opening in the stator, indexing means on said marginal portion of the base, and means through which the rotor is rotatively locked to the shaft including a spring member fixed to the end of the shaft having a radially extending finger cooperating with said indexing means on the marginal portion of the base, and cooperating contacts on the rotor and stator.

7. An electric switch as defined in claim 6 wherein integral members on the metal base and notches formed in opposite edge portions of the aperture in the stator have interfitting relation to fix the stator and metal base in rigid assembly.

8. An electric switch as defined in claim 6 wherein integral members on the metal base and notches formed in opposite edge portions of the aperture in the stator have wedging fit circumferentially of the path of rotation of the shaft.
